ATTORNEY

UNITED STATES PATENT OFFICE.

HERMAN L. GREVE, OF NEW YORK, N. Y.

MAILING WRAPPER FOR PHOTOGRAPHS.

Application filed January 17, 1925. Serial No. 2,974.

My invention relates to mailing wrappers and the object of my invention is to provide a suitable mailing wrapper for photographs which will properly protect the picture in transit through the mails, will embody stiffness and light weight and in which the photograph may be quickly inserted or removed without danger of injury and which may be reused for the same purpose if desired.

Referring to the drawings which form a part of this specification,

Figure 1 is a perspective view of the wrapper closed ready for mailing.

Figure 2 is a plan view of the wrapper in open condition.

Figure 3 is a plan view of a wrapper showing a modified form of holding band.

Figure 4 is a longitudinal sectional view, 20 of the wrapper taken in line 4—4 of Figure 1, with the photograph held therein and the flap portions being also shown in dotted lines.

A, indicates the body portion of the wrapper, 25 per which consists of flexible card board which is blanked out in the form shown in Figures 2 and 3, comprising two side flaps A' A' and two end flaps A² A² respectively.

B, indicates a corrugated straw-board, 30 which is of proper length and breadth to correspond to the area of the body portion A. A band C, of strong manila paper extends longitudinally over the straw-board and its ends C'—C' are cemented to the upper side of the body portion A, to which the under side of the straw-board is also cemented.

The space left between the top of the straw-board and band is just sufficient to 40 permit the photograph D, to be inserted under said band, which band is of sufficient width to prevent the photograph from any movement relative thereto after it has been placed thereunder. The band shown in Figure 3 consists of two portions indicated by C' and C², one end of each of which is cemented to the body portion A as described for band C, and the free ends C' and C² are gummed on their under sides, and after the

photograph is placed in the wrapper, the 50 ends C'—C² are drawn tight and cemented together, thereby firmly holding the photograph in proper position in the wrapper, after which the end flaps A²—A² respectively are folded inward above the band, 55 and then the side flaps A'—A' are folded over and the soft metal clips D—D which are secured to the flaps A²—A² respectively, are passed through the holes E formed in the flaps A' and then bent over the ends of 60 the upper flap A' as illustrated in Figure 1, to hold the parts together.

Having thus described my invention I claim as new:

1. A mailing wrapper for photographs 65 comprising a central body portion having narrow end flaps and wide overlapping side flaps formed therewith, a reinforcing straw board covering and cemented to the central body portion, a substantially wide, loose 70 band extending from end to end overlying the straw board, for retaining a photograph positioned therebeneath, said end flaps and side flaps being foldable over on the band and the central body portion in a flat condition completely covering the same, fastening 75 means attached to the end flaps, said side flaps having registration openings for the passage of said fastening means for locking all of said flaps and protecting the 80 marginal edges of the said photograph.

2. A mailing wrapper for photographs 85 comprising an outer casing of card board material having side and end flaps formed integral therewith, a plate of stiff straw-board cemented to the inner face of said casing and conforming thereto in length and width, a substantially wide flexible band having free ends held between said casing and plate and extending thereover and having its free ends provided with adhesive material to secure said ends together and hold a photograph firmly in position thereunder.

Signed at Brooklyn, in the county of 95 Kings and State of New York, this 31st day of December, A. D. 1924.

HERMAN L. GREVE.
